UNITED STATES PATENT OFFICE.

JOHN O. NEIKIRK, F LOMBARD, ILLINOIS, ASSIGNOR TO RODGER BALLAST CAR COMPANY, A CORPORATION OF MAINE.

D. OP-DOOR FOR RAILWAY-CARS.

1,344,208.

Specification of Letters Patent. Patented June 22, 1920.

Application filed August 6, 1917. Serial No. 184,600.

To all whom it may concern:

Be it known that I, JOHN O. NEIKIRK, a citizen of the United States, and resident of Lombard, in the county of DuPage and 5 State of Illinois, have invented certain new and useful Improvements in Drop-Doors for Railway-Cars, of which the following is a specification.

This invention relates to railway cars of 10 the type more particularly known as general utility cars, which have drop doors hinged to the underframe and extending beneath certain of the members of the under-frame, and the invention has for its object 15 to improve the construction of such cars by providing means for minimizing the leakage of material therefrom and for strengthening the doors so as to adapt the cars to meet the various requirements for 20 successful commercial operation.

These and other objects are accomplished by providing a drop door comprising a piece of material having corrugations formed therein for giving strength to the 25 door and also being of Z-section, the flanges giving added strength to the door and the same being arranged to prevent leakage.

The invention is illustrated on the accompanying sheets of drawings in which,

30 Figure 1 is a fragmentary plan view of a freight car embodying my invention;

Fig. 2 is a fragmentary sectional view of the same;

Fig. 3 is a fragmentary plan view of my 35 improved door;

Fig. 4 is a sectional view of the same door taken in the plane of line 4-4 of Fig. 3, and

Fig. 5 is another sectional view of the 40 same door taken in the plane of line 5-5 of Fig. 3.

The various novel features of my invention will be apparent from the following description and drawings and will be particularly set forth in the appended claims.

My invention is illustrated in connection with a railway freight car supported on wheels 10 and including side plates 11 which are reinforced by stakes 12. Spaced center 50 sills 13 and 14 are arranged lengthwise of the car and secured to the tops thereof is a cover plate 15 which spans the center sills. Suitably supported at the sides and also upon the cover plate 15 at each end of the 55 car is a relatively elevated floor portion 18.

Intermediate the ends of the car and below the level of the floor portion 18 at each end of the car are oppositely arranged doors 19 and 20, which are of Z-cross section. To withstand the heavy service to which they 60 are subjected, the body portions of the doors, which may be made of metal, are provided with corrugations 21, the depth of which increases toward the middle of the door, giving the lower portion of the door 65 a general tapered effect extending downward toward the middle of the door. The upper or top portion of each of the doors is straight and normally lies in a horizontal plane. The corrugations do not extend 70 entirely across the door, there being plane portions 22 and 23 adjacent the flanges 24 and 25, the former of which extends downwardly at right angles to the main portion of the door and the latter flange 25 of 75 which extends upwardly at right angles to the main portion of the door. The corrugations in the body of the door add greatly to the strength of the door, this being especially true where the depth of the corrugations is greatest along the middle of the door, as shown. The flanges 24 and 25 also add to the strength of the door.

By referring to Fig. 2 it will be noted that the upwardly extending flanges 25 of each of the doors is connected to a hinge 26 which in turn is secured to one of the center sill members, whereupon these pivotally mounted doors may be swung or dropped downwardly to permit outward dumping 80 of the load to either side of the car. The operation of the doors 19 and 20 is controlled by shafts 27 extending along the sides of the car and around which chains 28 are wound, one end of each of the chains 95 being connected to the front or outer portions of the doors. If it is desired to unload the car, it is merely necessary to actuate the shaft 27 in a manner to permit the doors 19 and 20 to drop or swing about their pivots. 100 It will be noted that the outer portion of the doors engage stop members 29 and that the downwardly extending flanges 24 also engage the downwardly extending flanges 30 of the stop members 29. Not only do the 105 flange portions 24 and 25 of the door greatly strengthen the same to withstand the heavy service, but they also prevent leakage. On each side of the car shedding members 31 connect the side members 11 with the stop 110

members 29. It is apparent from the above description that I have provided a car of the type described, in which the drop doors extend beneath the underframe members and 5 are provided with flanges so arranged to cooperate with the frame of the car as to minimize the leakage of material. This is a matter of great importance since it greatly lessens claims for damage arising from loss of 10 material in transit. Further, I have provided a door which is strengthened by this arrangement of flanges and, if desired, by the construction of the body of the door so that it will withstand the heavy service to 15 which these cars are subjected.

It is evident that there may be various modifications of the arrangement herein shown and described, and it is my intention to cover all such modifications which do not 20 involve a departure from the spirit and scope of my invention as set forth in the following claims.

I claim:

1. A drop door for railway cars, the top 25 portion of which is in a single plane and the under portion of which is provided with corrugations extending in the line of flow of the dumpable material and being deeper at an intermediate point than at other 30 points.

2. A drop door for railway cars having a body portion with corrugations therein extending from side to side, said door having flanges extending upwardly and downwardly respectively from the body portion for strengthening purposes.

3. A drop door for a railway car, comprising a body portion having its top in a single plane and having corrugations extending in the line of flow of the dumpable material, the depth of said corrugations increasing toward the middle of the door, and flanges extending from the body portion of the door for giving strength to the same.

4. In a railway car, the combination of frame members, a corrugated door having a body portion and flange portions extending therefrom, one of said flanged portions being pivotally connected to one of said frame 50 members and the other flange portion arranged adjacent the other frame member to prevent leakage past said door.

5. In a railway car, the combination of a center sill member, a side frame member, 55 and a corrugated door having a body portion and upwardly and downwardly extending flanges, the upwardly extending flanges

being pivotally connected to said sill member and the other flange portion being associated with the other frame member to prevent leakage.

6. In a railway car, the combination of a center sill member, a member having a stop portion and a downwardly extending flange, and a corrugated drop door having a body 65 portion and upwardly and downwardly extending flanges, the upwardly extending flange being pivotally connected to said sill member and the downwardly extending flange being arranged adjacent the downwardly extending flange of said member, the door being limited in its upward movement by the stop portion of said member.

7. A car having an underframe comprising a center sill taking the draft and buffing strains and the usual cross members, doors hinged to the center sill and extending therefrom beneath the cross members toward the sides of the car, and flanges arranged upon the edges of the doors coöperating with the frame members of the car.

8. A car having a center sill taking the draft and buffing strains and the usual cross members, doors hinged to the center sill and extending therefrom beneath the cross members toward the sides of the car, said doors being provided along their longitudinal edges with oppositely extending flanges.

9. In a railway dump car, the combination with the body of the car, of a hinged door forming part of the bottom of the car and adapted to assume an inclined position for dumping, comprising a sheet steel panel formed with corrugations extending in the direction of movement of the cargo when dumped, which merge one into the other so that the panel has a sinuous configuration in cross section.

10. In combination with the body of a railway dump car, of a door, means for hinging the door to the bottom of the car body, means for supporting the edge of the door opposite the hinges when the door is closed; the door comprising a sheet metal panel formed with corrugations which extend substantially from the hinged edge of the door to said opposite edge.

Signed at Chicago, Ill., this 27th day of July, 1917:

JOHN O. NEIKIRK.
